Patented June 6, 1922.

UNITED STATES PATENT OFFICE.

OSCAR F. HOLMBERG, OF CHICAGO, ILLINOIS.

EGG-DIPPING MACHINE.

1,418,927.

Specification of Letters Patent. Patented June 6, 1922.

Application filed March 8, 1920. Serial No. 364,264.

To all whom it may concern:

Be it known that I, OSCAR FRITHIOF HOLMBERG, a citizen of the United States, residing at Chicago, in the county of Cook 5 and State of Illinois, have invented certain new and useful Improvements in Egg-Dipping Machines, of which the following is a specification.

My invention relates to egg-preserving means and has particular reference to an apparatus for dipping eggs in large quantities in a preserving or treating fluid and for automatically timing the duration of the dipping process. With these general objects 10 in view my invention consists in the novel construction of machine hereinafter described in detail, illustrated in the accompanying drawing and more particularly pointed out in the appended claims.

20 In the drawing—

Figure 1 is a perspective view of a machine embodying my invention.

Figure 2 is a section taken substantially on the line 2—2 of Figure 3.

25 Figure 3 is an enlarged detail view taken from Figure 1.

Figure 4 is a section taken substantially on the line 4—4 of Figure 1, partly broken away, drawn to an enlarged scale.

30 Figure 5 is an enlarged face view of the trigger and associated mechanism shown in Figure 1 and substantially an elevation of the details shown in Figure 4.

The frame of the machine herein shown, 35 which may be varied in any suitable way, consists of a series of uprights or posts 2, 3, 4, 5 and 6 and horizontal bars 7, 8, 9 and 10 mounted on posts 11 and 12 and on the uprights 5 and 6 and all supported on a base

40 13. The frame members may be angle irons such as 5 and 6 shown in cross section in Figure 4, which for the members 7 to 10 provide frame-like ledges 15, 15 adapted to support liquid-containing trays or tanks.

45 Provision is made for two such dipping trays for the purpose of the present illustration of my invention, by dividing the space formed within the members 7 to 10 by a pair of similar angle irons 16 and 17. The 50 spaces 18 and 19 thus produced may in a simple manner for the present purpose represent dipping tanks, or skeletons therefor, or the relation or position of such tanks with reference to the remaining portions of the

55 machine herein shown. 20 represents a movable section of track, the remaining por-

tion of the track (not shown), being fixed or immovable and a continuation of the movable section 20 in its normal position shown in full lines in Figure 1.

60

The track section 20 is mounted on an arm or lever 21 which is pivoted at 22 between the parallel flanges bearing the numerals 5 and 6 in Figure 4, which in Figures 1 and 4 represent a pair of uprights, angle iron posts, or standards. On the arm 21 is mounted in any suitable manner a counter weight 23 which may be made adjustable along the arm to vary its leverage according to requirements. A stop 24 (Fig. 4) between the standards 3 and 4 limits the downward movement of the free end of the arm or lever 21, which end is free to swing in a slot or opening 24' formed by spacing apart the frame standard consisting of the pair 75 of angle irons 3 and 4. Egg-containers, not shown, are hung from trolley wheels or grooved rollers on the track and when on the movable section 20 of said track are dipped into the tanks represented by the 80 framed spaces 18 and 19, and one of the objects of the hereinafter described mechanism is to accurately time the dipping automatically, which is necessary, especially where the liquid is heated to a high temperature. The arm 21 and its track section 20 is swung down to the dotted line position shown in Figure 1 to dip the load on said track section (not shown) first, say, in the 85 tank 19 and then in the tank 18, by means of a foot lever 25 that is pivoted at 26 between the standards 5, 6 and 3, 4. This foot lever is connected with the arm 21 by means of a connecting-rod 27 the ends of which are pivoted at 28 and 29 to the arm 90 21 and the lever 25, respectively.

95 Provision is made to catch and hold raised the free or rear end of the arm 21 for the required length of time in the dotted line position and to hold the track section 20 with 100 its load lowered into the dipping tank 18 or 19. The mechanism for this purpose consists of a catch or latch 30 that is pivoted at 31 to a plate 32 hung for free swinging movement on a pivot 33 mounted on the 105 standard 3. On the plate 32 is a stop pin 34 which limits the downward movement of the latch 30 and holds it in its normal position across the space 24 between the standards 3 and 4, as shown in Figure 1. The latch 30 is, however, movable upward to clear the 110 space between the members 3 and 4, or to

permit the arm 21 to swing by said latch upwardly when the foot-lever 25 is operated. The latch 30 then holds the arm 21 in its dotted line position until released by the 5 mechanism now to be described.

The referred to free swinging movement of the plate 32 upon which the latch 30 is pivoted, is normally restrained by a pin 35 that is movable longitudinally through a 10 bore 36 that passes through a flange of the standard member 3 and registers with a similar bore 37 in the plate 32 hanging in its normal position. The pin 35 is secured to a right angle flange 38 on a swinging member 39 pivoted at 40 to an ear or lug 41 which projects forwardly from the member 3. From the lower end of the swinging member 39, which is a trigger release member, projects forwardly an arm or 15 lug 42 to which is secured a curved contact shoe or plate 43 which is engaged by the hereinafter described automatic timing mechanism to swing the trigger release member. On the flange portion 38 of said member 39 is the pin or detent finger 35 which is normally engaged with the normally concentric bores 36 and 37, and when the said detent finger is withdrawn from said bores the downward pressure of the 20 rear or free end of the arm 21 will swing the latch 30 downward and out of the path 24' by swinging the plate 32 on its pivot 33 to the left (Figures 1, 4 and 5). After the arm 21 has returned to its normal full 25 line position shown in Figure 1 gravity holds the latch plate 32 and its latch 30 in their normal position shown clearly on a large scale in Figure 5.

The release of the arm 21 in its arrested, 30 or dotted-line position by disengagement of the detent finger 35 which, as shown, holds the base-plate 32 for the latch 30 in normal position, is effected through the contact shoe or plate 43 being engaged and swung out 35 of the circular path of either one of two rods or arms 44 and 45 which extend horizontally from the respective ends of a cylinder or fluid substance container 46 which is mounted on a collar 47 which rotates on a 40 pair of trunnions, shafts or journals 48 and 49 which are rotatably mounted in the standards 2 and 3. On the shaft 49 is revolvably mounted the upper end of an arm 50. To the latter is pivoted at 51 one end of a 45 curved connecting bar or rod 52. The other end of the connection 52 is pivoted at 53 to an elbow bearing-bracket 54 that is secured to and is projected from the side of the arm 21 as shown in Figure 1. When 50 said arm 21 is swung to its dotted line position by pressing down the foot lever 25 the connecting bar 52 will swing the arm 50 forwardly against the rear side of the arm 45 and thereby swing the container 46 to 55 its horizontal or dotted line position. In this

position said container is held the required length of time by the automatically-operating device hereinafter described, and which consists of shifting the center of gravity from one end of the container to the other 70 end thereof, or from the forward toward the rear end, looking at Figure 1. When the center of gravity has moved to the rear of the vertical plane of the container's axis of rotation said container will swing another 75 quarter revolution which carries the contact arm 45 against the shoe 43 swinging the latter back and out of its way, thereby withdrawing the detent finger 35 which holds the plate 32 against rotation on its pivot 33, 80 and permitting the arm 21 to push aside the latch 30 and its plate 32 as one member, and return to its normal position.

The container 46 is partially filled with any suitable flowing substance and is divided by a partition 55 into two chambers 56 and 57 which communicate with each other through valve controlled bores or ports 58 and 59. Said ports are intersected by bores 60 and 61 with which valve plugs 62 and 63 have threaded engagement, whereby said plugs are adjustable into and across the paths of the bores 58 and 59 to vary the volume of flow therethrough. The chamber 57 in the position in which the parts are 95 shown in Figures 1 and 3 is filled with a suitable liquid, such as water, mercury, or any other substance adapted to pass freely through the openings 58 and 59. In Figure 1 (in which the container 46 is assumed to 100 be made of transparent material) the dotted line position of said container or cylinder 46 shows the chamber 57, held by its connection with the arm 21 in its raised or arrested position, elevated a little higher than the 105 chamber 56, which, at the beginning of the elevating movement is the upper and empty chamber. This elevation of the filled chamber 57 assists the flow through the ports 58 and 59 from said filled chamber to 110 the rearward or empty chamber. When the flow has transferred the greater portion of weight of fluid to the chamber 56 the weight will be removed from the arm 50 on 115 which the container is supported horizontally by the arm 45 and the container will swing another quarter revolution causing the arm 45 to strike the shoe 43 and reversing the positions of the chambers 56 and 57, placing the latter at the top; also substituting the arm 44 for the arm 45 as the next acting arm to operate the release mechanism, and restoring the lever arm 21 to swing the movable track-section 120 into normal position and in alinement with the fixed track-section, a broken away abutting end of which is shown in Figure 1 and labeled 20'; the obvious details of one of numerous means of track support being omitted from this fixed track portion 20' 130

which may be continued at the left hand end (Fig. 1) of the swinging track section 20, or caused to abut in the same manner as that shown for the fixed track portion 20'.

5 From the upper body portion of the base-plate 32 for the latch 30 projects a curved and pointed lug or toe portion 64 which is engaged by a stop-pin 65 that projects from the standard 3 and which prevents the plate 32 from swinging back beyond normal position, or into the pathway 24' of the arm 21.

10 For the purpose of facilitating the flow from one of the chambers 56 and 57 to the other, provision is made to permit the air 15 displaced by liquid in the receiving chamber to escape into gradually enlarging air space above the liquid in the discharging chamber and relieve the tendency to form a vacuum there. For this purpose a pair of oppositely 20 projecting air-tubes 66 and 67 are mounted in corresponding bores through the partition 55 which, as indicated most plainly in Figure 2, are arranged laterally of the valve-ports 58 and 59 and extend to points near 25 the respective ends 68 and 69 of the container 46, as shown in Figures 1 and 6. In the dotted line position of the container 46 in Figure 1, as the air is displaced by liquid flowing into the chamber 56 it is permitted 30 to escape into the air-tube 67 and into the elevated end of the chamber 57, which in Figure 3 is there the lower end.

35 In operation, egg-containing receptacles are suspended from and along the stationary track 20' and successively moved onto the track section 20 into position over the first dipping tank outlined as 19, the foot lever 25 is then pressed down to its dotted line position to lower the track section 20 and dip 40 its container into the tank 19, the free end of the lever arm 21 lifting the catch 30 against the resistance of its spring 30' anchored on a pin 30" and held against return movement on said catch resting on its stop pin 34. 45 The length of time that the egg container (not shown) is held in the solution in the tank 19 is automatically determined by the time required for liquid, or its equivalent to overbalance the container and swing its 50 chamber to the position of the full line position of the chamber 57 and cause the arm 45 to swing the member composed of the elements 43, 39, 38 and 35 out of its path to

disengage the detent finger 35 from the bore 37 in the plate 32. The detent finger 35 being released from the plate 32 the weight of gravity operating at the rear and free end of the arm 21 will cause it to tilt aside the catch 30 and its plate 32 now free to swing on its pivot 33. If the eggs are to be treated 55 a second time the egg container will be moved on the track section into position over the tank 18, the foot lever again pressed and the above described operation repeated. The container may then either be removed from 60 the dipping track section 20 or continued to the dipping track section 20 or continued to the left on a stationary track 20' to some 65 more distant point.

I claim as my invention:

1. The combination with a track-rail, of a pivoted lever-arm on which said track-rail is mounted, lever-operated means for swinging said lever-arm and track-rail in one direction, and automatically operating devices for swinging said lever-arm and track-rail in 75 the opposite direction.

2. The combination with a stationary track-rail, of a movable track-section normally aligned with and forming a part of said stationary track-rail, lever-operated means 80 for lowering said movable track-section away from said stationary track-rail, means for holding said movable track-section in its lowered position, a timing device, and means set in motion thereby for restoring 85 said movable track-section to its normal position.

3. The combination with a bearing-frame, of a lever-arm pivoted on said frame, means for temporarily supporting a tank on said 90 frame, a track-rail having a movable section mounted on said lever-arm, means for swinging said lever-arm to lower said movable section over the supporting means for said tank, an automatically operating catch- 95 mechanism for temporarily arresting said lever-arm and lowered position of said movable section, a timing mechanism and means for variably adjusting same, and means actuated by said timing mechanism for restoring 100 said movable section into its normal position as a portion of said track-rail.

In testimony whereof I have hereunto signed my name.

OSCAR F. HOLMBERG.
